PUZZLE

Louis Ray Lane, Habana, Cuba

Application August 31, 1934, Serial No. 742,301

5 Claims. (Cl. 273—153)

My invention relates to improvements in puzzles, and it consists in the combinations, constructions and arrangements herein described and claimed.

5 An object of my invention is to provide a device of a simple nature and one which apparently can be easily solved, but which actually is comparatively difficult.

10 A further object of the invention is to provide a puzzle in the shape of a ball having a movable member cooperating therewith for producing the result desired, and in which the ball also serves as a protecting cover for the movable member and for certain figures carried by the latter.

15 Other objects and advantages will appear in the following specification and the novel features of the invention will be particularly pointed out in the appended claims.

20 My invention is illustrated in the accompanying drawing forming part of this application, in which:

Figure 1 is a face view of one embodiment of the invention showing the parts in position to complete or solve the puzzle.

25 Figure 2 is a view of the interior movable member, which in the present instance is a ball.

Figure 3 is a section along the line 3—3 of Fig. 1.

Figure 4 is a view similar to Fig. 1 showing a modified form of the puzzle, and,

30 Figure 5 is a view similar to Fig. 2 showing a modified form of the interior ball.

In carrying out my invention I make use of a ball 6 which may be of any suitable material, such as wood, hard rubber, papier-mâché, or the like, and which is preferably hollow, although one made solid could be used. On the surface of this ball 6 I may place one or more figures 7. In Fig. 2 I have shown these figures as being made up of the card symbols for hearts, diamonds, spades and clubs, but other figures, pictures, letters, etc. might be used.

35 Enclosing the inner ball 6 is an outer ball 8, which in the present form of the invention, is opaque. It is provided with openings 9 which correspond with the positions of the figures 7, so that when the balls are in the relative positions shown in Fig. 1, these figures will be seen through the openings 9 in the outer ball or shell. In this particular form of the device any one of these openings constitutes means for access to the interior ball 6, which is rotatable within the outer shell so as to bring the figures 7 out of registration with the openings 9.

40 In the use of the device, the inner ball is first moved by placing the tip of the finger through

one of the openings 9 and bringing it into frictional engagement with the outer surface of the inner ball when by moving the finger the inner ball will be rotated so as to bring the figures out of registration with the opening. The puzzle 5 of course is to bring the figures all into registration with the openings. It might first appear that if one of the figures were brought into registration all would be, and the puzzle would be solved, but such is not the case. Consider Figure 10 1. If the inner ball should be rotated on an axis perpendicular to the plane of the paper for instance, the central figure would remain in the central opening, but the other figures on the inner ball which are in view in Fig. 1 would have 15 disappeared. Conversely, if the player gets one figure centralized in an opening it does not necessarily mean that the others will appear in their respective openings, and the puzzle is only solved when this condition occurs.

20 In Figs. 4 and 5 I have shown a modified form of the device in which an inner ball 10 is covered by a transparent shell 11, the inner ball being movable around a common center in any direction, as described in connection with Figs. 1, 2 25 and 3. In this instance the inner ball is provided on its outer surface with figures such as those shown at 12, 13 and 14, while on the outer side of the transparent ball or shell 11 are figures 15, 16, 17, which may register with the figures 12, 13 30 and 14 in the manner of a jig-saw puzzle to form a completed figure which in the present instance is the triangle A, B, C.

35 In this form of the device the normal position of the inner ball 10 with respect to the outer ball is such that the figures 12 to 17 inclusive are out of registration. This is accomplished by thrusting the finger through the opening 18 in the outer transparent shell 11, and frictionally revolving the inner ball 10 in any direction.

40 In this form of the device, as in the other, it may seem to be easy to bring the inner ball into the proper position to solve the puzzle, as by forming the triangle A, B, C, because those forms or figures on the inner ball can be seen through the 45 transparent shell. Such however is not the case since one often tries to manipulate the inner ball to bring a certain form or figure into registration with one on the outer shell, only to find that the part does not fit, as one often finds in the ordinary jig-saw puzzle. It is the apparent ease with 50 which the puzzle may be solved and the real difficulty in solving it that forms one of the main features of entertainment of both forms of this device.

It is obvious that other registering forms or figures might be used in connection with a transparent shell than those shown in Fig. 4. The triangle shown may be only one of a number of forms or figures, portions of which are shown at 5 19, 20, 21 and 22. The arrangement may be such that when one figure such as the triangle A, B, C may be formed, other figures may be formed at the same time, or each figure might be formed 10 separately and constitute a puzzle in itself.

I claim:

1. A puzzle comprising an outer spherical shell having an opening, an inner ball rotatable in any direction, and means on said shell and said 15 ball adapted to be brought into registration by the movement of the ball for solving the puzzle.
2. A device of the type described comprising an outer spherical shell having an opening, a ball disposed within said outer shell substantially in 20 contact therewith and rotatable about the center of the shell, visible figures carried by the ball, and means carried by the shell and adapted to register with the figures on the ball when the ball is moved to a predetermined position.
- 25 3. A device of the type described comprising an outer spherical shell having a plurality of open-

ings, an inner ball snugly fitting the shell and rotatable in any direction about the center of the shell, said ball having figures adapted to be brought into registration with said openings when the ball is moved to a predetermined position. 5

4. A device of the type described comprising a transparent shell, a ball snugly fitting within the transparent shell and being provided with a plurality of figures, said shell having disposed thereon a plurality of figures adapted to register with 10 the figures on the ball to form a completed object, and having an opening whereby the ball may be rotated within the shell by frictional means applied through the opening.

5. A device of the type described comprising 15 a ball having thereon a representation of a portion of an object, an outer transparent shell snugly surrounding the ball and having thereon the representation of a different portion of the same object and being provided with a finger opening 20 for giving access to the ball whereby the latter may be rotated to bring the portion of the object on the ball and the portion of the object on the shell into registration to complete the object. 25
